[57] CLAIM

The ornamental design for an element of the shoe sole, as
shown and described.

DESCRIPTION

FIG. 1 is a perspective view of an element of a shoe sole
showing my new design;

FIG. 2 is a side elevational view of the element of a shoe sole
shown in FIG. 1;

FIG. 3 is a top plan view of the element of a shoe sole shown
in FIG. 1; and,

FIG. 4 is a rear elevational view of the element of a shoe sole
shown in FIG. 1.

The broken line showing of the remainder of the shoe sole
and rest of the shoe is for illustrative purposes and forms no
part of the claimed design.
